UNITED STATES PATENT OFFICE

2,345,151

ELECTROMAGNETIC DEVICE

William R. Ray, Beverly Hills, Calif.

Application June 10, 1940, Serial No. 339,765

3 Claims. (CL 200—87)

My present invention relates to electromagnetic switching devices or relays, and particularly to those of the "sensitive" type wherein a contact-actuating armature is arranged to be attracted, against a bias, by an electromagnet upon the passage through its coil of a small amount of current—usually direct current or rectified alternating current.

The armature of such a relay is so arranged that, when attracted, it is as close as possible to the attracting pole face of the electromagnet core without actually being in engagement therewith. Engagement of the armature and the pole face must not be permitted on account of the danger of magnetic "sticking" of the armature due to the residual magnetism which remains when the core is deenergized. Furthermore, for maximum sensitivity, the permissible movement of the armature, when it is released from its attracted position, must be minute. Consequently, the adjustment of such a relay is delicate and is difficult of accomplishment even by a skilled mechanic. It is therefore an object of my invention to provide means whereby such a relay can be fully adjusted by the movement of a single part, such as a screw.

A specific object of my invention is the provision, in a relay of the character indicated, of a member limiting the movement of the armature both toward and away from the core and so adjustable as to position the armature with respect thereto.

A further specific object is to provide the aforesaid armature-limiting member with a contact element cooperable with one carried by the armature, whereby uniform contact spacing is maintained regardless of the attracted position of the armature with respect to the core.

Other objects and advantages of my invention will be found in the description, the drawing, and the appended claims.

For complete understanding of the invention, reference may be had to the following detailed description and accompanying drawing, wherein:

Figure 1 is a plan, with cover removed, of a relay embodying my invention;

Figure 2 is a section taken along the line 2—2 of Fig. 1;

Figure 3 is a detail section of the armature adjusting means of the relay shown in Figs. 1 and 2; and

Figure 4 is a fragmentary view of conventional relay adjusting means, shown only for the purpose of comparison.

In Figs. 1-3 of the drawing, the numeral 11

indicates a base of molded insulating material on which is mounted, by a right-angle bracket 12, an electromagnet comprising a U-shaped core 13 which carries on its free arm 14 an energizing coil 15, the leads 16 of which are connected to terminals 17 provided on the base. Interposed between the bracket 12 and the supporting arm 18 of the core is a portion of an armature-retaining and core-holding member 19 of non-magnetic material, having a laterally bent portion 20 provided with an opening for receiving the end of the core arm 14 and holding it rigidly with respect to the other arm 18. The member 19 is fully described and claimed in the copending application of William A. Ray, Serial No. 318,520, filed February 12, 1940, which became Patent No. 2,324,109 on July 13, 1943.

Fulcrumed on the angularly formed end of core arm 18, and guided in an opening formed in the outer end portion of member 19, is an armature 21, longitudinal movement of which is limited by the cooperation of the inner edges of the opening in member 19 with notches formed in the corresponding edges of the armature. A contractile spring 22, connected to the upper portion of the armature and to a lug 23 formed by a bent-up portion of member 19 extending through an opening in the core arm 18, urges the lower end of the armature away from the pole face of core arm 14.

Mounted on the base 11, by a bracket 24, is an adjusting device, generally indicated at 25 and comprising a tubular member 26, the reduced left-hand end of which is rigidly secured in an opening in the upper portion of bracket 24. Slidably in the bore of member 26 is a rod 27 which carries on its outer end a U-shaped member 28, rotation of which is prevented by ears 29 formed on its inner arm and engageable with the edges of bracket 24. Tightly threaded on the inner end of rod 27, and slidably in an enlarged portion of the bore of member 26, is a button 30. A spring 31, compressed between this button and the shoulder formed by the enlargement of the bore of member 26, urges the rod to the right, movement in that direction being limited by a plug 32 threaded in the right-hand end of member 26.

Cooperable with a contact element 33, carried by the lower end portion of the armature which extends between the arms of the U-shaped member 28, is another contact element 34, pressed in an opening in the end of rod 27 which projects through the inner arm of member 28. Insulatingly mounted in the outer arm of member 28

is a stop rivet 35, engageable in the unattracted position of the armature with the riveted-over stem of the armature contact element 33. Means for connecting the switching elements of the relay in an electrical circuit are provided by a terminal 36, connected by a flexible wire 37 to the armature, and by the foot 38 of the bracket 24. Secured to the base 11 is a metal mounting plate 46 having upturned edges on which a cover or housing 47 is mounted.

To adjust the relay, it is only necessary to move the rod 27 in or out, by turning the screw plug 32, until there is the required gap between the pole face of core arm 14 and the armature, when the latter is in its attracted position. This gap is usually less than 0.005 inch and may best be determined by the use of a non-magnetic feeler gauge.

The contact gap, or angular distance through which the armature is permitted to move, is fixed and thus remains the same in any adjustment of the relay. As a sensitive relay of the type disclosed is usually only required to control a light load, the wear or burning-away of the contacts is inappreciable. If variation of the contact gap is desired, the stop 35 may be made adjustable. For maximum sensitivity, a contact gap of 0.005 inch or less is usually employed.

As a sensitive relay often loses its adjustment in shipment due to vibration and jar, the simple adjusting means of my invention has particular utility in that it enables the average mechanic to accurately restore the adjustment.

The advantage of the adjusting means which I have provided can best be appreciated by comparison with the conventional adjusting means disclosed in Fig. 4, wherein the numeral 39 indicates the free end portion of a contact-carrying armature which is limited in its movement by a stop screw 40 and a contact screw 41, threaded in brackets 42 and 43 and locked in adjusted position by nuts 44 and 45, respectively. In adjusting, both nuts are loosened, and the armature properly positioned with respect to its core by movement of the contact screw, after first backing out the stop screw. The contact screw is then locked, care being taken that its position is not disturbed. The contact gap is then similarly adjusted by first moving and then locking the stop screw.

While I have shown the adjusting means of my invention embodied in a simple relay, it is obvious that it also has utility in connection with other types of relays, such as those of the polarized type wherein the armature is repulsed instead of attracted or is biased to a neutral position between opposed magnetic poles. Also, other forms of switching means, carried by the adjusting member, may be provided for actuation by the armature. I intend, therefore, that my invention be limited only by the scope of the appended claims.

I claim as my invention:

1. In an electromagnetically operated switching device: a core, an energizing coil for said core, an elongated armature mounted for angular movement about one of its ends in directions toward and away from said core and biased in the last-named direction, means limiting the movement of said armature in both of said directions and comprising a member having spaced-apart portions between which the free end portion of said armature extends, said member being movable that said armature is moved therewith in said directions, to position it with respect to the core, a first contact element carried by the free end of said armature, and a second contact element cooperable with said first contact element and mounted on one of said spaced-apart portions.
2. In an electromagnetically operated switching device: a core, an energizing coil for said core, an armature pivoted for movement in directions toward and away from said core and biased in the last-named direction, means limiting the movement of said armature in both of said directions and comprising a U-shaped member between the arms of which a portion of said armature is disposed, said U-shaped member having a laterally extending arm mounted for reciprocable movement in directions transverse to the axis of said armature whereby said armature can be moved in said directions to position it with respect to said core, a first contact element carried by said portion of said armature, and a second contact element cooperable with said first contact element and mounted on one of the arms of said U-shaped member.
3. In an electromagnetically operated switching device: a U-shaped core; an energizing coil for said core; an elongated armature pivoted at the free end of one arm of said core, and having a portion extending beyond the free end of the other of said core arms and movable in directions theretoward and away therefrom; means biasing said armature in said last-named direction; means limiting the movement of said armature in both of said directions and comprising a U-shaped member between the arms of which said extended portion of the armature is disposed; said U-shaped member having a laterally extending arm mounted for reciprocable movement in directions transverse to the axis of said armature, whereby said armature can be moved in said directions to position it with respect to the free end of the other of said core arms; a first contact element carried by said extended portion of the armature; and a second contact element cooperable with said first contact element and mounted on one of the arms of said U-shaped member.

WILLIAM R. RAY.
